FREDRICK J. KERBEL, OF SEATTLE, WASHINGTON, ASSIGNOR TO ROBERT J. NODERER,
OF SEATTLE, WASHINGTON.

THEATER-CHAIR.

1,176,221.

Specification of Letters Patent. Patented Mar. 21, 1916.

Application filed January 5, 1915. Serial No. 579.

To all whom it may concern:

Be it known that I, FREDRICK J. KERBEL, citizen of the United States, residing at Seattle, in the county of King and State of Washington, have invented a certain new and useful Improvement in Theater-Chairs, of which the following is a specification.

My invention relates to improvements in chairs that are adapted for use in theaters, 10 music halls and like places of public assembly and the object of my improvement is to provide chairs which are so constructed that they can be disposed within an auditorium in series of rows, which rows 15 may be disposed closer together than has been possible with theater chairs heretofore employed, without discommodeing the occupants of such chairs, and which are adapted to permit such occupants to remain seated while persons are traversing through 20 the space between them and backs of the chairs in the row immediately in front of them, and a further object of my improvements is to provide such chairs each with a 25 seat and a chair-back of such form as will adapt them to be suspended in such manner that such seat and chair-back may be caused to swing backwardly from their normal positions without engaging with a raised portion 30 of a floor that may be present immediately back of such chair, as might be the case when rows of such chairs are disposed in a balcony of an auditorium, and as will adapt them to resist sidewise and torsional 35 movements in response to movements of the occupant. I attain these objects by devices illustrated in the accompanying drawings in which—

Figure 1 illustrates a chair embodying 40 my invention by a view in vertical mid-section showing some parts in side elevation; Fig. 2 is a fragmentary view of the same in vertical section on broken line z , z of Fig. 1; Fig. 3 is a fragmentary view in 45 horizontal section of the same showing parts on broken line z , z of Fig. 2; Fig. 4 is a fragmentary view in vertical section showing parts of the same on broken line y , y of Fig. 1, and Fig. 5 is a fragmentary 50 view in horizontal section on broken line w , w of Fig. 1, showing other parts of the same.

Referring to the drawings, throughout 55 which like reference numerals indicate like parts, 6 indicates one of the two vertical

side portions of a chair frame which may be secured to the floor of an auditorium by screws (not shown) which may extend through holes 7 that are disposed in the flanges at its bottom end and which two 60 side portions may be rigidly connected together at a suitable distance by a cross-brace 8 which is secured to the rear edges of said side portions. These side portions are preferably of cast-iron and are each 65 provided with flanges that extend around its edges, as shown, and are further provided each with an arm-rest 9, preferably of wood, which is disposed securely on its top edge.

Two suspension bars 10 and 11 are pivotally suspended from bosses 12 disposed on the inner side of each of the side portions 6 of the chair frame in positions parallel with each other to adapt them to swing 70 backwardly and forwardly in a plane that is parallel with the planes of said side portions 6, and such bars 10 and 11 are each secured in its position on its respective boss 12 by means of a screw 15 and a washer 13 75 which is provided with a dowel pin 14 that projects into the boss 12 to prevent said washer 13 from turning in response to friction due to a swinging of the bar 10, as more clearly shown in Fig. 3.

A chair-back 16 is provided with two supporting brackets, like the supporting brackets 17 illustrated in Figs. 1 and 2, which brackets 17 are secured to the rear side of the lower portion of the chair-back 90 16, opposite each other, and each is formed to extend from the rear of the chair-back 16 around the edge thereof, thence forwardly and obliquely downward for such distance as will adapt it to be pivotally articulated with the lower end portions of the adjacent bars 10 and 11, as shown, to be supported thereby in such manner that said bars 10 and 11 shall always be parallel with 95 each other irrespective of their swinging movements. The chair-back 16 thus mounted on supporting brackets of the form of the supporting bracket 17 provides greater space between the bottom edge of said chair-back 16 and the floor whereby chairs embodying my invention may be adapted to operate when disposed in the balcony of a theater where the floor is raised immediately back of each row of chairs since the chair-back 16 may be moved backwardly without 100 105 110

causing its lower edge portion to engage with the raised floor behind it.

The pivots which articulate the suspension bars 10 and 11 with the supporting bracket 17 comprise, each, a screw 18 which extends freely through a hole in the lower end portion of each of such suspension bars and thence screws into a screw-threaded hole provided in a thickened portion of a lug 19 that is integral with such supporting bracket 17, and to prevent the pivots 18 from unscrewing and getting loose I provide a set-screw 20 which is disposed, as shown, to extend upwardly through such thickened portion of the lug 19 to engage the side of the pivot 18 to hold it securely in its position in an obvious manner.

Each of the suspension bars 10 is longer than the suspension bars 11 to adapt it to extend downwardly as shown for a considerable distance below the point of its articulation with the supporting bracket 17 and to such downwardly extended end portions of the oppositely disposed suspension bars 10 are secured the angularly formed end portions of a cross brace 21 by means of rivets 22 and 23, thus to rigidly unite such suspension bars 10 to obviate any tendency they might have to move sidewise or to move independently backward or forward in response to movements of the occupant of the chair; and in order that the suspension bars 10 and 11 may be normally and yieldingly maintained in a vertical position I have provided a yielding detent spring 24 one of whose ends is secured to the adjacent front edge of the lower portion of the side portion 6 of the chair frame and which is formed to extend rearwardly to engage an indented portion of it with the head of the rivet 23 as more clearly shown in Fig. 5.

The detent spring 24, being disposed to act on the lower end of the extended portion of the suspension bar 10 at a great distance from its point of suspension, need be adapted to yieldingly exert only a slight pressure on the head of the rivet 23 in order normally to maintain such suspension bar in a vertical position.

Disposed to extend between the two supporting brackets 17 is a chair-seat 25 which is pivotally attached to the supporting bracket 17 by means of oppositely disposed pivot bearing brackets, like the pivot bearing bracket 26, the pivot bolt 27, the washer 28 and the nut 29, as shown more clearly in Fig. 4, whereby such chair-seat 25 may be moved to swing from its normal horizontal position upwardly and backwardly to lean against the chair-back 16 in a manner well known and to prevent the front portion of the chair-seat 25 from swinging downwardly below its horizontal plane I have provided a lug 30 integral with the supporting bracket 17 with which the adjacent bearing

bracket 26 may engage to limit the downwardly swinging movement of such front portion of the chair-seat 25.

Obviously the side portions 6 of the chair frame are of such construction as will adapt them each to serve as one of the side portions of the chair frame of another adjacent chair, for instance, four similar side portions, like the side portions 6, would be employed in a row of three chairs and such chairs of such row would be rigidly united by means of the cross brace 8 comprising an integral strip secured to the back edges of each of such side portions and by reason of their secured position on the floor of the auditorium.

It is important that the brackets 17 be pivotally attached to the suspension bars 10 and 11 at points far below the chair-seat 25 in order that such pivotal points shall travel in the path of a larger circle when the chair-seat 25 is moved rearwardly thus to cause such chair-seat 25 to be raised only a little higher than the plane of its normal position even though such rearward movement be throughout its maximum distance.

The operation of chairs embodying my invention may be described as follows: When a chair is unoccupied the chair-seat 25 is disposed with its front portion leaning against the chair-back 16 thus to permit a person to pass in front of the chair close to the front edges of the side portions 6, and when the chair is to be occupied the chair-seat 25 is turned swingingly downward to a horizontal position, as shown in Fig. 1, in which position it will be supported by the lug 30 and the pivot bolt 27 and in such position the suspension bars 10 and 11 normally will be yieldingly held in a vertical position by detent spring 24 which normally engages with the head of the rivet 23.

When seated if the occupant wishes to permit a person to pass in front of him, he simply braces his feet on the floor and presses his body backwardly with a force sufficient to disengage the detent springs 24 thus to release the suspension bars 10 to permit them to swing rearwardly to the position indicated by dotted lines in Fig. 1, and after such person has passed him he lets himself swing forward until the chair-seat 25 is in the normal position shown in Fig. 1.

Obviously changes may be made in the forms, dimensions and arrangement of parts of my invention without departing from the spirit thereof.

What I claim is:

1. A chair of the class described which embodies two pairs of seat-suspension bars, the front bar of each pair being longer than the rear bars thereof; a cross brace disposed to extend between and fastened to the lower end portions of said front bars, thus rigidly to unite them; and yielding detent means

operatively associated with the lower end portions of said front bars whereby said front bars may be yieldingly maintained substantially in their natural position of suspension.

2. A chair of the class described, which embodies two pairs of suspension bars, a seat associated with said suspension bars to be swingingly suspended thereby; a cross-brace disposed to extend between and be fastened to the lower end portions of corresponding ones of the bars of said pairs thus to rigidly unite them; and yielding detent

means operatively associated with the lower end portions of the rigidly united bars 15 whereby said bars may normally and yieldingly be secured in their natural position of suspension.

In witness whereof, I, hereunto subscribe my name this 24th day of December A. D., 20 1914.

FREDRICK J. KERBEL.
